UNITED STATES PATENT OFFICE.

LLOYD BROWN, OF LOS ANGELES, CALIFORNIA, ASSIGNOR TO SILENT DRAMA SYNDICATE, A TRUSTEESHIP, LLOYD BROWN AND ALEXANDER GRAYDON, TRUSTEES.

PICTURE STUDIO.

Application filed January 20, 1920. Serial No. 352,766.

To all whom it may concern:

Be it known that I, LLOYD BROWN, a citizen of the United States, residing at Los Angeles, in the county of Los Angeles, State 5 of California, have invented new and useful Improvements in Picture Studios, of which the following is a specification.

This invention relates to studios and studio constructions particularly adapted to 10 the production of motion pictures; although, as will be seen after consideration of the following description, the invention is not at all limited to use for the production of motion pictures. It is a general object of 15 the invention to provide a studio arrangement and construction such as will facilitate the easy and rapid arrangement of scenes, facilitate convenience to the operators and actors, and provide means whereby desired 20 lighting effects may be had by control of natural illumination, so that the necessity of resorting to artificial illumination is minimized or done away with.

Although, as I say, my studio is not necessarily limited to the production of motion pictures, it will facilitate an understanding 25 of the invention to describe my studio as it is designed particularly for the production of motion pictures. From such a 30 specific description of the studio as designed particularly and used specifically for the production of motion pictures, the broad aspects and features of my invention, as well as detailed features applied particularly 35 for this purpose, will be apparent. Accordingly, I now proceed to give a description of that specific and preferred form of the invention which is adapted particularly to the motion picture art.

40 In the production of motion pictures there are a great many disadvantages inherent in studio constructions and arrangements and inherent in operations therein carried on, that my invention seeks to overcome. 45 Among some of these disadvantages I may mention particularly the lack of concentration of properties and effects. As will be seen later, my studio accomplishes great concentration and puts everything in very convenient relation so that the setting up and shifting of scenes, etc., may be accomplished 50 with the minimum of labor. Furthermore, the managing offices and quarters for properties and dressing quarters are all concen-

trated in a small area together with the 55 stage upon which scenes are set and upon which the acting takes place, so that a minimum amount of moving about is required of the persons concerned in the production of a picture. 60

Furthermore, artificial illumination to a great degree has to be resorted to in the present production of motion pictures because of the changing illumination available from natural means. For instance, when an 65 interior scene is set up, it must be set in some fixed position and co-ordination with reference to the sun. The natural illumination of this scene of course varies from hour to hour during the day; and even if 70 the natural sun illumination is suitable for such an interior scene at some particular hour of the day, it will not be suitable at any other time.

It is one of the objects of the invention, 75 and one of its primary features, that it provides means for control of the natural sun illumination in such a way as to make natural illumination available for interior scenes, etc.; and, furthermore, makes natural 80 illumination easily controllable throughout the hours of the day. It is a feature of my invention that it provides means not only for originally obtaining the desired illumination but also for controlling natural 85 illumination so that the illumination of any particular scene may be kept the same from hour to hour; and so that, within a concentrated arrangement and construction, any desired kind of illumination may be had, 90 either direct, open sunlight, or sunlight diffused in such a way as to cast no shadow, or sunlight either in its full intensity or reduced to any desired degree.

95 For the purposes of now giving a better and more detailed understanding of my invention, I now enter into a detailed description of a preferred form of studio construction adapted particularly to motion picture work; and from this description the broad 100 and general features of my invention, as well as the details of the present preferred form thereof, will be apparent. For these purposes I refer to the accompanying drawings in which—

105 Fig. 1 is a side elevation, showing my improved studio arrangement and construction, with parts shown in vertical section;

Fig. 2 is a plan view thereof; Fig. 3 is a vertical detail section showing the construction of several of the parts; and Fig. 4 is a detail perspective showing construction and arrangement of the canopy.

I provide a housing structure which may be made of an exterior plan configuration suitable to the effective use of ground space. (It is my design in the use of my invention, 10 to use a number, perhaps a large number of these studio structures in juxtaposition to each other, and in conjunction with a common laboratory, shop buildings, etc.) Thus the exterior structure may be square or rectangular in plan, with four exterior walls 10. The façades of these exterior walls may be ornamented in any suitable manner, or these walls may be exteriorly so constructed and arranged that any desired ornamentation or scenery may be placed before them, so that the exterior may be used as 20 scenery background for taking of certain pictures, street scenes, etc. Arranged around this structure, in hollow square arrangement, are the various rooms which may be used as manager's and director's offices, and office for assistant director, and property rooms and the various dressing rooms. These rooms are designated by the numerals 11, 12 and 13.

The roof of the structure forms the floor 15. This floor has, in its central part, a circular opening 15^a; and a circular rotatable stage 16 fills this opening and forms a continuation of the floor 15. For all purposes and intents, when the circular stage is at rest, the stage 16 and the floor 15 form one continuous floor. It will be observed that the roof which forms the stationary floor 15 projects into close proximity, on substantially the same level, to the edge of the stage 16; and in the form of the invention shown 35 in Fig. 2, this stationary floor 15 projects inwardly, at the corners at least of the stationary structure, over the open space or quadrangle enclosed by the stationary structure, so that a very substantial stationary floor or working area is provided adjacent the rotatable stage.

Arrangement for access to the interior space 18 within the hollow square of rooms and beneath the stage 16, and thus to the various rooms through suitable doors 19, may be arranged for in any suitable manner. For instance, there may be entrances at 20 and 21, and from these entrances an inclined way 22 may lead up to the floor 15. It is obvious that instead of this ramp 22, a 45 stairway might be provided. An inclined way is preferable to stairs, and the way may be of a suitably gentle slope to facilitate the easy transportation of heavy or large effects.

The circular stage 16 may be constructed 50 in any suitable manner and is carried upon

a circular track 30. Wheels 31 mounted on the underside of the stage floor run upon this track. These wheels may be flanged so as to keep the stage centered; or the stage may be wholly centered by the action of the vertical shaft 32. Central vertical shaft 32 is suitably mounted with respect to the stage and rotates therewith. This shaft may have at its lower end a bearing 33 and it carries a large gear 34 driven by a pinion 35 from a motor 36. The controls for motor 36 may be located in any suitable position, and preferably at some place upon the floor 15, so that the person controlling the motor may observe the position of the stage. Thus, for 60 instance, the controls may be located in a small control house at 37.

Central vertical shaft 32 extends on up above the stage and is the supporting member for the canopy. Canopy C may be constructed with any suitable frame work. For instance, it may have a central ring 40 surrounding shaft 32, and radiating arms 41 carrying the outer circular frame member 42. This canopy is constructed as lightly as 70 possible consistent with suitable strength. The frame is movable vertically upon central shaft 32 and is supported by cables 43 which are attached to ring 40 and pass over pulleys 44 and thence pass down to a small 75 winch 45 operated by motor 46. The controls for motor 46 may also be in control house 37. Pulleys 44 are mounted in a ring 47 preferably rotatable about the shaft 32. The ring 40 fits shaft 32 loosely so that the 80 canopies may be moved rotatively around the shaft and may also be moved up and down on the shaft.

The canopy frame may be covered with fabric or any other suitable covering. For instance, if a fabric is used, it may be supported upon the frame and upon supporting wires 50; and cords 51 and 52 may be arranged in any of the well known manners so that the fabric 53, which will be arranged 90 in sections, may be extended out to cover the whole canopy frame or may be reefed back against frame members 41 of the canopy. By such an arrangement any one or more of the canopy fabrics may be entirely 95 reefed in or may be entirely extended; so that all of the canopy may be thus covered, or parts of it may be uncovered, or the whole may be uncovered. Certain parts of the canopy frame may be covered with a heavy fabric, such as heavy canvas that will transmit 105 relatively little light; and other sections, say three of four sections (for instance, the ones shown reefed in Fig. 2) may be of thin muslin to act as light diffusers, transmitting a 110 large amount of diffused light.

The canopy, as hereinbefore described 115 may be moved vertically and it is apparent that it may also be rotated around the shaft 32. When the canopy is set in any desired po- 120

sition, then it is guyed down securely by guy ropes 55. And these guy ropes also are the mediums through which the canopy may be rotated about the vertical shaft to any desired position relative to the shaft and relative to the stage 16: It will thus be seen that the stage may be rotated to any desired position relative to the floor 15 and to any desired ordination or any desired position relative to the position of the shaft. Also it will be seen that the canopy may be raised or lowered so as to put it higher above or closer down upon the settings upon stage 16; also that the canopy covering may be reefed or extended to suit the lighting requirements. And, further, the canopy may be rotated with reference to the stage; and this is very convenient because, if certain parts of the canopy fabric are reefed, then it is very easy to turn the open portions of the canopy over that part of the stage where open light is desired. Furthermore, after any portions of the canopy covering are arranged to give just the light desired, that light is easily maintained upon the setting by suitable rotation of the stage and also by suitable relative rotation of the canopy from time to time. It will thus be readily recognized that any desired lighting effect may be produced, and when produced may be maintained by proper movement of the stage and canopy.

Furthermore, the movement of the stage greatly facilitates the operation of setting up and taking down scenes. On a stage of this character (which may, for instance, be about eighty feet or more in diameter) a number of settings may be put up; and it is very desirable and convenient to be able to turn any desired part of the stage to a point immediately adjacent the runway 22; so that properties and effects brought up the runway may be immediately transferred to the stage without having to be carried around the floor; although the floor provides means for moving around the stage from setting to setting as desired. A manager may operate several companies of actors at the same time in the concentrated space upon such a stage, and may do so very easily because he is in close contact with all such companies at all times.

There is an advantage also in the elevated arrangement of the stage and floor; in that I am enabled, by such an arrangement to put the directing offices, property rooms, dressing rooms, etc., close to the stage itself, and at the same time not have them in a position where they cut off light from the edges of the stage. In the usual arrangement of studios, if the dressing rooms are close to the stage itself, they cut off light from the edge portions of the stage, and from the stage in general; or they must be placed at such a distance as to be somewhat inconvenient. By elevating the floor and

stage I obtain unobstructed light for the stage; and at the same time I am enabled to efficiently utilize the space below the floor and stage for the offices and rooms, etc.

While I have given a description with some particularity and detail, I have done so not only for making the preferred form of my invention intelligible and readily understood, but also for the purpose of illustrating and typifying my invention, and not for the purpose of pointing out its limits. Believing my invention to be broad in its scope and character, I do not limit myself to the particular things herein set forth, but only consider my invention limited in scope as may be expressed in the following claims, which are to be read and interpreted in a broad and fundamental as well as in a specific sense relating to the structure herein described.

Having described a preferred form of my invention, I claim:

1. In a picture studio construction, the combination of an elevated rotatable stage, a stationary roofed and chambered structure surrounding said rotatable stage with its roof surface forming a stationary floor substantially level therewith, and an inclined approach leading to said stationary floor and stage.

2. In a picture studio construction, the combination of an elevated rotatable stage of substantially circular formation, a substantially rectangular roofed and chambered structure surrounding said stage with its roof forming a stationary floor substantially level with and closely fitted to said rotatable stage, an entrance in said stationary structure below the stationary floor to give access to the chambered sections, and leading through said stationary structure to the roof thereof to give access to the stationary floor and stage.

3. In a picture studio construction, the combination of an elevated rotatable stage of substantially circular formation, a stationary structure surrounding said stage, the roof of which forms a stationary floor substantially level and in continuation of said stage, a canopy support rising from said stage, a canopy mounted on said support, means for raising and lowering said canopy relative to said stage, and means extending from said canopy to said stationary structure for maintaining said canopy in any adjusted position.

4. A picture studio construction, embodying in combination a rotatable stage, a rotatably adjustable canopy support, and a canopy carried thereby above the stage, said canopy having relatively opaque and translucent light diffusing parts.

5. A picture studio construction, embodying in combination a rotatably and vertically adjustable canopy support, a canopy carried

- by said support above the stage, said canopy having relatively opaque and translucent light diffusing parts.
6. A picture studio construction, embodying in combination a rotatable stage, a rotatably and vertically adjustable canopy frame, a covering carried by said frame above the stage adapted to be extended or folded upon the canopy frame.
- 10 7. A picture studio construction embodying in combination, a rotatable stage, a rotatably and vertically adjustable canopy frame and light diffusing canopy coverings carried by said frame above the stage adapted to be extended or folded upon the said frame.
- 15 8. A picture studio construction embodying in combination a central elevated rotatable stage, a stationary structure surrounding the stage and having a roof forming an elevated floor surrounding the stage and forming a continuation thereof, said structure including below said floor suitable rooms for offices and dressing rooms; and 20 a canopy supported above the rotatable stage and rotatably adjustable with reference thereto.
- 25 9. A picture studio construction embodying in combination a central elevated rotatable stage, a stationary structure surrounding the stage and having a roof forming an elevated floor surrounding the stage and forming a continuation thereof, said structure including below its floor suitable rooms for offices and dressing rooms; and a canopy 30 having light diffusing portions supported above the rotatable stage and rotatably adjustable with reference thereto.
- 35 10. A picture studio construction, embodying in combination a central elevated rotatable stage, a stationary structure surrounding the stage and having an elevated floor surrounding the stage and forming a continuation thereof, said structure including below its floor suitable rooms for offices and dressing rooms; a canopy support and a canopy supported above the stage, and 40 rotatably and vertically adjustable with reference thereto.
- 45 11. A picture studio construction, embodying in combination a central elevated rotatable stage, a stationary structure surrounding the stage and having an elevated floor surrounding the stage and forming a continuation thereof, said structure including below its floor suitable rooms for offices and dressing rooms; a central vertical shaft rising from the stage, a canopy frame mounted upon said central vertical shaft to 50 be vertically adjustable thereon and rotatably adjustable thereon with reference to the shaft and to the rotatable stage, and canopy coverings arranged upon the canopy frame and adapted to be spread or reefed 55 as desired.
12. A picture studio construction, embodying in combination a central elevated rotatable stage, a stationary structure surrounding the stage and having an elevated floor surrounding the stage and forming a continuation thereof, said structure including below its floor suitable rooms for offices and dressing rooms; a central vertical shaft rising from the stage, a canopy frame mounted upon said central vertical shaft to 60 be vertically adjustable thereon and rotatably adjustable thereon with reference to the shaft and to the rotatable stage, and canopy coverings arranged upon the canopy frame and adapted to be spread or reefed 65 as desired; some of said canopy coverings being relatively opaque and others being relatively translucent.
13. In a picture studio construction, the combination of a movable stage, a canopy support, a canopy mounted on said support above the stage and independently movable relative thereto, said canopy having relatively shiftable parts capable of adjustment to vary the light passing through different 70 sections of said canopy.
14. In a picture studio construction, the combination of a movable stage, a canopy support, a canopy mounted on said support above said stage and shiftable vertically 75 relative to said stage, said canopy having relatively shiftable parts capable of adjustment to vary the light passing through different sections of said canopy.
15. In a picture studio construction, the combination of a movable stage, a canopy support, a canopy mounted on said support above said stage and shiftable rotatably relative to said stage, said canopy having relatively shiftable parts capable of adjustment to vary the light passing through different sections of said canopy.
16. In a picture studio construction, the combination of a movable stage, a canopy support, a canopy mounted on said support above said stage and shiftable rotatably and vertically relative to said stage, said canopy having relatively shiftable parts capable of adjustment to vary the light passing through different sections of said canopy.
17. In a picture studio construction, the combination of a rotatable stage, a centrally disposed canopy support rising from said stage, a canopy mounted on said support, means for raising and lowering said canopy, said canopy comprising areas made up of shiftable members to vary the light passing through sections of said canopy.
18. In a picture studio construction, the combination of a rotatable stage, a centrally disposed canopy support rising from said stage, a canopy mounted on said support and rotatable thereon independently of said stage, means for raising and lowering said

canopy, said canopy comprising areas made up of shiftable members to vary the light passing through sections of said canopy.

19. In a picture studio construction, the combination of a stationary structure surrounding an open space and provided with rooms, a roof for said structure extending inwardly over a part of said open space and forming a stationary floor, a rotatable stage mounted in said open space substantially 10 on a level with and forming a continuation

of said roof, a canopy support rising centrally from said rotatable stage, a canopy mounted on said support, and means for raising and lowering said canopy.

15

In witness that I claim the foregoing I have hereunto subscribed my name this 31st day of December, 1919.

LLOYD BROWN.

Witness:

VIRGINIA I. BERNINGER.
